UNITED STATES PATENT OFFICE.

GUST BILDIR, OF DAYTON, OHIO.

MACHINE FOR CLEANING WINDOWS AND WALLS.

1,119,339

Specification of Letters Patent.

Patented Dec. 1, 1914.

Application filed July 2, 1914. Serial No. 848,554.

To all whom it may concern:

Be it known that I, GUST BILDIR, a subject of the King of Greece, residing at Dayton, in the county of Montgomery and State of Ohio, have invented certain new and useful Improvements in Machines for Cleaning Windows and Walls; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in machines for cleaning windows and interior walls.

The object of the invention is to provide a window and wall-cleaning machine through means of which the work of cleaning windows and walls is greatly facilitated, and the danger attending the work of cleaning the outsides of windows of office buildings is avoided.

To the above ends, the machine is adjustable and consists in the main of a series of extensible members, telescoping one within the other and constituting a brush-supporting arm. The brush which may be of any suitable form is connected to a flexible shaft and is rotatable through suitable gearing which in turn is set in motion by a crank-driven shaft.

The details of the invention will appear from the description to follow and the accompanying drawings to be considered therewith.

Referring to said drawings in general terms, Figure 1 is an elevation of my improved window-cleaning machine, parts of the extensible brush-supporting arm being broken out to bring the illustration within prescribed limits. In this view a section of the window-sill and wall of a building is shown, as well as a sectional view of a portion of a window. Fig. 2 is a sectional elevation of a portion of the machine on a larger scale and looking in the direction of the arrow in Fig. 1. A portion of the telescopic or extensible brush-supporting arm is broken off to facilitate illustration. Fig. 3 is a sectional view of the frame or gear box and the gearing through which movement is imparted to the brush, the band-wheel and clutch. Fig. 4 is a top plan view of the

clamp by means of which the machine is mounted on a window-sill in an operative position as in Fig. 1. Fig. 5 is a sectional view of the upper end of the telescopic or extensible arm showing the brush and its flexible connection. Fig. 6 is an enlarged cross sectional view of the extensible arm with the sections thereof telescoped. Fig. 7 is a detail view of the flexible band forming the connection and means by which the brush-supporting arm is extended or shortened. Fig. 8 is a view similar to Fig. 5 showing an elongated form of brush.

Throughout the description to follow, and the accompanying drawings which have been thus briefly referred to, similar reference characters indicate corresponding parts.

At the beginning it should be stated that the form of supporting means for the machine may vary according to the work to be done. When used for interior wall-cleaning, the clamping means, such as is illustrated in Figs. 1 and 5, would of necessity be dispensed with and the frame 1 of the machine supported on any suitable form of base, or the lower surface 2 of the base may engage the floor directly. It will be understood that the machine is manipulated by one hand grasping the expandable brush-holding arm, while the other hand rotates the crank. The expandable brush-holding arm consists of an outer casing consisting of a suitable number of telescoping sections, fitting one within the other and being extensible or contractible by means presently described. The lowermost section 3, is rigidly attached to the frame or gear box, which, it will be observed, is open. The telescoping outer casing thus made up of the members 3, 4 and 5 is stationary as to rotary movement. Within this casing is arranged the expandable brush-supporting arm made up of a series of tubular telescoping members 6, 7 and 8, the number of which may vary according to the length required. These inner sections 6, 7 and 8 have a splined connection one with the other so as to cause one section to rotate the other. The lowermost section 6 is rigidly secured to the enlarged part of a driving shaft 9, said shaft 9 being supported in a bearing 10 which is a part of the frame 1. The lower end of the outermost section 3 of the outer casing is also secured to this bearing 10. Leaving the shaft 9 for a moment; any suitable form of brush 11 (Fig. 5, or Fig. 8) is supported in the up-

per end of the innermost section 8 of the extensible arm by means of a flexible shaft consisting of a stem 12 which is detachably secured within said section 8 by means of a pin 13 on the stem which fits in notches 14 in the end of section 8. Secured to the stem 12 is a spring 15 the upper end of which is fixed to a tube 16 which is contracted to receive the stem 17 of the brush, said stem having a detachable pin and slot connection with the tube 16. The flexible brush support thus described lies within a goose-neck 5' which is a continuation of the upper section 5 of the outer casing. Reverting to the shaft 9, Fig. 2, the lower end thereof has upon it a pinion 18 which engages a crown-gear 19 fixed to the driving shaft 20 journaled in the gear box or frame 1. The shaft 20 is supported at three points in said frame 20 as is apparent from Fig. 1 and has a crank or handle 21. It will be apparent that a rotation of the crank 21 results in rotating the brush through the connections specified.

The expandible casing and tubular arm 25 consisting, as before specified, of the members 3, 4, 5, 6, 7, 8 and 16, is manipulated by means of a metallic band 22 one end of which is slidably maintained in engagement with the outer side of the casing by passing 30 through a suitable number of guides or keepers 23 and the other end of which is secured to the upper section 5 of the casing. As is shown in Fig. 2, the said band passes through a guide 24 which is suspended from the bearing 10 and thence through a guide slot 25 in said bearing. A band-wheel 26 runs loose on the shaft 20, the periphery of which is provided with a suitable number of teeth 27 which enter corresponding openings 28 40 in the band 22. It will be understood that the band is snugly conducted through the guides and between the surfaces of the casing and therefore has no chance to buckle in the operations thereof in elevating or 45 lowering the casing sections and the brush-supporting arm sections. In Fig. 7 is shown one simple manner of uniting the band to the upper section 5 of the casing. The band-wheel 26 is provided with lateral clutch 50 parts 29 (see Fig. 3). Adapted to engage therewith is a clutch member 30 splined to the driving shaft 20, such engagement is effected when it is desired to extend or withdraw the casing members 3, 4, 5 and the 55 brush-supporting members 6, 7 and 8. As is shown in Fig. 3, the clutch members are disengaged and the band-wheel is locked against rotation. Such a condition is obtained by means of a dog 31, which is normally controlled by a spring 32. When the clutch members are disengaged, as in Fig. 3, the clutch member 30 controls the spring 32. The clutch members are normally separated by the spring 33, and said clutch is 65 operated from a shifting rod 34 which is

coupled to a rod 35 extending to and connected with a grip-lever 35'. This grip-lever 35' is pivoted to an upright handle 36. The implement or machine is manipulated by one hand grasping this handle and is thereby changed in its position to move the brush over the wall or window, while the other hand of the operator turns the crank 21.

In Fig. 1 the brush is illustrated in engagement with a window 37. The machine is there shown to be mounted on a windowsill 38 by means of a suitable clamp 39 which is manipulated by an adjusting device 40. A central member or round support 41 is a feature of the clamp. As shown in Fig. 2, this round support 41 enters a corresponding recess, in the base of the frame 1 and provides means for supporting the frame in a manner which enables the machine to be tilted to either side of a perpendicular line, while being operated. Whenever it is necessary to extend or withdraw the brush-supporting arm, the grip-lever 35' is pressed in to throw in gear the clutch; the band-wheel 26 is then caused to rotate in the direction in which the shaft 20 is turned.

A powder-spraying device may be conveniently used during the operations of the machine to spray cleansing powder upon the window or wall. This may be a spray nozzle 42 attached to the end of a flexible tube 43 extended in the vicinity of the handle 36, as partially illustrated in Fig. 1. These features, however, form no part of my invention and I have, therefore, not deemed it necessary to fully illustrate the same.

It will, of course, be understood that changes of a more or less detail in character may be made without departing from the underlying principles of my invention, which, in the main, contemplates a machine the essential features of which consist of extensible brush-supporting members, with means for rotating the particular brush-supporting arm and adjusting the same in the same power-transmitting operation.

I claim.

1. In a machine of the character specified, a supporting frame, an expandible and contractible casing, an expandible and contractible brush-supporting arm mounted within said casing and movable therewith, means for extending and contracting the said casing and therewith the said arm, means for rotating said arm independently of said casing, and a common shaft from which both of said means are operated.

2. In a machine of the type specified, a supporting frame, an expandible and contractible casing mounted thereon, an expandible and contractible brush-supporting arm mounted in said casing and subject to the movements of said casing, a flexible band by which such movements are imparted to

said casing, gearing by which the said arm is rotatable independently of said casing, and a common shaft from which the aforesaid means are operated.

- 5 3. In a machine of the character specified, the combination with a supporting frame, and means for holding said supporting frame in its operative positions, of a telescopic casing, a brush-supporting arm
10 mounted in said casing, means for withdrawing and extending the sections of said

telescopic casing and therewith the brush-supporting arm, means for rotating said brush-supporting arm, and a shaft from which the telescopic casing and the brush- 15 supporting arm are operated.

In testimony whereof I affix my signature, in presence of two witnesses.

GUST BILDIR.

Witnesses:

JAMES A. LIANOS,
MATTHEW SIEBLER.
